UNITED STATES PATENT OFFICE.

GABRIEL STREICH, OF OSHKOSH, WISCONSIN.

DESIGN FOR A FIRE-HOSE-WAGON BODY.

SPECIFICATION forming part of Design No. 28,577, dated May 10, 1898.

Application filed February 14, 1898. Serial No. 670,239. Term of patent 7 years.

To all whom it may concern:

Be it known that I, GABRIEL STREICH, a citizen of the United States, residing at Oshkosh, in the county of Winnebago and State of Wisconsin, have invented and produced a new and original Design for a Fire-Hose-Wagon Body; and I do declare the following to be a full, clear, and exact description of the same, reference being had to the accompanying drawing, forming a part thereof.

In the accompanying drawing the figure is a perspective view of a fire-hose-wagon body embodying my design.

The leading feature of my design consists of an approximately rectangular-shaped wagon-body having a longitudinally and vertically arranged central partition, vertically - arranged rollers, and a horizontally-arranged roller at the rear end of the wagon-body.

In the drawing, A represents the wagon-box body, which is rectangular in shape and has a horizontally-arranged slatted floor a and a centrally-arranged vertical partition B. Along and above the sides of the wagon-body appear hand-rails C, which extend from the front end of the wagon slightly beyond the

rear end of the same and terminate in vertically-arranged hand-rails c, at the lower end of which appears a step D. At the front end of the wagon-body and above the same appears a seat E, and at the forward end of the wagon-body appears a foot-rest F. The wagon-body also appears provided with wheels G and a combined mud-guard and step H, of a curved form, located between the front and rear wheels and extending over both of said wheels. A pole I also appears extending from the front end of the wagon, and beneath the rear end of the wagon appears a tool-box J of rectangular shape, and beneath the step D another tool-box of rectangular shape.

Having now described my design, what I claim as new, and desire to secure by Letters Patent, is—

The design for a fire-hose-wagon body, substantially as herein shown and described.

In testimony whereof I affix my signature in presence of two witnesses.

GABRIEL STREICH.
